US00D889257S

(12) **United States Design Patent** (10) Patent No.: **US D889,257 S**
Kukucka et al. (45) Date of Patent: **** Jul. 7, 2020**

(54) **ANTI-SLIP MULTIDIRECTIONAL DRIVER BIT**

(71) Applicant: **GRIP HOLDINGS LLC**, Brandon, FL (US)

(72) Inventors: **Paul Kukucka**, Brandon, FL (US); **Thomas Stefan Kukucka**, Brandon, FL (US)

(73) Assignee: **GRIP HOLDINGS LLC**, Brandon, FL (US)

(**) Term: **15 Years**

(21) Appl. No.: **29/709,794**

(22) Filed: **Oct. 17, 2019**

Related U.S. Application Data

(63) Continuation-in-part of application No. 16/107,842, filed on Aug. 21, 2018, which is a continuation-in-part of application No. 15/601,864, filed on May 22, 2017, now abandoned.

FOREIGN PATENT DOCUMENTS

WO 2017031333 2/2017

Primary Examiner — Cynthia R Underwood

(57) **CLAIM**

The ornamental design for an anti-slip multidirectional driver bit, as shown and described.

DESCRIPTION

FIG. 1 is a top perspective view of an anti-slip multidirectional driver bit showing my new design;

FIG. 2 is a bottom perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof; and,

FIG. 8 is a left elevated view thereof.

The broken lines showing of an attachment body in FIGS.

1-8 are included for the purpose of showing environmental structure and form no part of the claimed design.

1 Claim, 8 Drawing Sheets
